UNITED STATES PATENT OFFICE.

WINTHROP L. JACOBS, OF EAST ORANGE, NEW JERSEY, ASSIGNOR TO THE
HARTFORD CARPET COMPANY, OF HARTFORD, CONNECTICUT.

DESIGN FOR A CARPET.

SPECIFICATION forming part of Design No. 13,801, dated March 20, 1883.

Application filed January 25, 1883. Term of patent 3½ years.

To all whom it may concern:

Be it known that I, WINTHROP L. JACOBS, of East Orange, Essex county, New Jersey, have invented a new and original Design for 5 Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

The ground *a* is filled in with a system of small leaf sprays. This ground is traversed 15 by a system, *b*, consisting of an irregular network of conspicuous angular stems which bear, along their length or on short branching stems,

various gem-like flower figures and irregular angular leaf forms. These gems and leaf forms, which, with their connecting-stems, form the 20 system *b*—the foreground of the design—are larger in size and entirely different in shape and character from the leaf forms that constitute the background, as is clearly shown in the photograph.

25

I claim—

The design for a carpet, consisting of the gem and leaf system *b* and the ground *a*, substantially as shown and described.

WINTHROP L. JACOBS.
